UNITED STATES PATENT OFFICE.

JOHN DEPEW, OF NEW YORK, N. Y., ASSIGNOR TO IGNATZ LAUTER, OF NEW YORK, N. Y.

CAPACITATIVELY-ACTUATED LOUD SPEAKER.

Application filed February 12, 1926. Serial No. 87,974.

My invention relates to loud speakers of the kind suitable for use with radio broadcasting receivers, electrically operated sound amplifiers, wire and wireless telephone receivers, and various other relations in which 5 loud sounds are to be produced or controlled from exceedingly small initial variations in the electromotive forces or amperage of electric currents.

10 More particularly stated, I seek to produce a loud speaker provided with a diaphragm of insulating material actuated by the attraction and repulsion of stationary conductors of large capacity which are energized by 15 electrical charges varying in electromotive force from moment to moment, under control of an amplifying device, such as an audion tube.

I have made the discovery that in the manner just indicated a diaphragm can be so actuated as to produce considerable disturbance in the air, and thus to throw off sound waves resulting in sounds of great volume and fidelity of expression.

25 Other objects and aims of the invention, more or less specific than those referred to above, will be in part obvious and in part pointed out in the course of the following description of the elements, combinations, 30 arrangements of parts and applications of principles, constituting the invention, and the scope of protection contemplated will be indicated in the appended claims.

In the accompanying drawings which are 35 to be taken as a part of this specification, and in which I have shown merely a preferred form of embodiment of the invention:

Figure 1 is a view, partly a perspective and partly a diagram, showing one form of 40 my improved loud speaker and suitable electric circuits for use therewith.

Figure 2 is a section on the line 2—2 of Figure 1 looking in the direction indicated by the arrows.

45 Figure 3 is a section similar to Figure 2, but shows a form of my invention in which the mounting of the diaphragm is somewhat different from that appearing in Figure 2.

Figure 4 is a section similar to Figure 2, 50 but showing the diaphragm as mounted in still another manner.

Referring now to the drawings for describing in detail the structure therein shown:

55 Two plates 5, 6, made of metal and pro-

vided with holes 7, serving as acoustical apertures, are disposed parallel with each other and held in position by aid of bolts 8 carrying nuts 9 and sleeves 10 and 11, as indicated more particularly in Figure 2. The sleeves 10 and 11 are of insulating material and are so fitted together as to form joints, one of which is shown at 12. Encircling the sleeves 10, 11, are metallic washers 14, 15. These washers fit upon opposite sides of a diaphragm 13.

This diaphragm is preferably quite large, and is made of insulating material. Many different substances are suitable for use as the material for the diaphragm, among them being thin sheet celluloid, hard rubber, film sheets made from solutions of gun cotton dissolved in amyl acetate, or thin paper permeated with a suitable filling, such as a varnish. The substance which I employ, however, is cellophane preferably embossed. This substance is obtainable commercially in sheets of considerable size, each sheet having a thickness of not more than a thousandth of an inch.

As hereinafter more particularly set forth, differences of potential are developed between the plates 5 and 6 during the operation of my device, and as a consequence there are differences of potential developed between the metallic washers 14 and 15, shown more particularly in Figure 2. The washers 14 and 15 are close together, being separated by only the thickness of the diaphragm 13, and insulated from each other by this diaphragm. Thus each washer 14 and its mating washer 15 act like the walls of a small condenser. Since the plates 5, 6, act like the walls of a large condenser and are in metallic contact with the washers 14 and 15 with which they are associated, it follows that there is a considerable capacitative effect upon opposite sides of the diaphragm 13, and that this effect is localized to some extent, relatively to the diaphragm, by the metallic washers 14 and 15.

In some instances I prefer not to use the metallic washers 14 and 15, but to employ instead the structure shown in Figure 3. Here the diaphragm has the form indicated at 16, and is engaged upon its opposite sides by rubber washers 17 and 18. In this case the bolt 8 and its nut 9 are insulated from the metallic plates 5 and 6 by means of sleeves 19 and 20 of insulating material. In

this form of my invention the capacitative effect of the conducting members upon opposite sides of the diaphragm 16 is not localized as in the form shown in Figure 2, but on the other hand the distribution of the capacitative effect relatively to the diaphragm 16 is somewhat more uniform.

In the forms of my invention contemplated by Figures 1 to 3 inclusive the diaphragm is always held firmly, though resiliently, by its margin, and if desired may be under tension.

Where it is desired that the diaphragm be loose and free relatively to the plates 5 and 6 and parts connected therewith, I employ the form shown in Figure 4: Here the diaphragm appears at 21, and extending through a hole in it is a washer 22, of insulating material, engaging the plates 5 and 6. Extending through this washer and through the plates 5 and 6 is the bolt 8 and sleeves 10 and 11.

A pair of binding posts 23 and 24, carried by the plates 5 and 6, are used in connecting the plates 5, 6, with appropriate electrical circuits.

The plates 5, 6, are provided with feet 25, either made of insulating material or resting upon a surface of insulating material, and serving as supporting members for the loud speaker.

An aerial appears at 26, an audion tube at 27, a B battery at 28, an impedance at 30, a grounding switch at 31, and a ground at 32. An aerial wire 33 extends from the aerial 26 to the grid 34 of the audion tube 27, and the audion filament is shown at 35 and the audion plate at 36. The filament circuit appears at 37, and the A battery at 38, and included in the filament circuit in the conventional manner.

A wire 39 extends from the plate 36 to the binding post 23. The impedance coil 30 is tapped on to this wire, and connects the same with the B battery 28. Connected with the B battery 28 is a wire 40. Connected with this wire is a wire 41, leading to the binding post 24, and also a wire 42 which is connected with the grounding switch 31 and with a wire 43, the latter leading to the filament circuit 37. Whenever it is desired that the filament circuit be grounded the grounding switch 31 is closed, but if the filament circuit is to be left ungrounded the grounding switch 31 is left open.

Generally speaking, the action of the aerial 26 and audion tube 27 are the same as in well known forms of receivers. However, the connections and actions of the B battery 28 are different. The circuit through which a flow of current from the B battery 28 takes place may be traced as follows: B battery 28, wire 40, wires 42 and 43, a part of filament circuit 37, filament 35, through vacuum to plate 36, and thence

through a part of wire 39 and through impedance coil 30 back to B battery 28. It will be noted, however, that while no direct current from the B battery can pass through the loud speaker via wires 39 and 40, because the plates 5 and 6 are insulated from each other, these plates are nevertheless subjected to differences of potential, because they are bridged across the B battery 28. It will also be noted that variations in the electromotive force of the B battery must produce variations in the differences in potential between the plates 5 and 6, and that these differences in potential are qualified by the action of the impedance coil 30, so that the plates 5 and 6 are affected one at a time, as far as practicable, by any given change of potential. In other words, any variations in the current of the B battery may be considered as the equivalent of an electrical impulse traveling from the B battery to the plates 5 and 6 respectively, but reaching the plate 6 a trifle earlier than the plate 5, owing to the impedance or retardation of the impedance coil 30. It follows as a necessary consequence that the diaphragm 13 is alternately attracted and repelled by each of the plates 5 and 6. Because thus actuated, the diaphragm is moved back and forth with a vibratory motion, and gives off sound waves.

By the use of the metallic washers 14 and 15, above described with reference to Figure 2, and consequently by localization of the capacitative effect exerted upon opposite sides of the diaphragm 13, the action of the diaphragm is for many purposes greatly improved.

On the other hand, in instances where I use the form of my invention above described with reference to Figure 3, the diaphragm 16 has greater freedom of movement, owing to the resilience of the rubber washers 17 and 18, and for many purposes this increased freedom of movement of the diaphragm, and particularly near its outer edges, is preferable to the localized capacitative effect above described.

In the construction shown in Figure 4 the diaphragm, shown at 21, has still greater freedom, and in some instances this is fully as desirable as the other advantages above described with reference to the constructions contemplated by Figures 2 and 3.

For purposes of illustration I have shown the diaphragm in Figures 3 and 4 as spaced quite a distance from each of the capacitative plates. This is merely for the purpose of rendering the principles clear and easy to apply. In practice the plates 5 and 6 are very close together, and the diaphragm as close to each of them as occasion may require. In the form shown in Figure 4 the diaphragm 21 may be in loose contact with each of the plates 5 and 6. This is upon the principle that with the diaphragm thus

mounted it has sufficient freedom of movement to perform vibratory movements of audio frequency sufficient in magnitude to give off sound of considerable volume.

5 In the form of my invention shown in Figure 2 the metallic plates 5 and 6 are provided with bosses 44, integral therewith and in close engagement with opposite faces of the diaphragm 13. By this arrangement the 10 bosses 44 tend to localize the condenser action of the plates, or in other words act like smaller condenser plates, so that the diaphragm is actuated more strongly.

I find that by using bolts 8 and parts 15 accompanying the same, in locations other than at the corners of the condenser plates 5 and 6, and especially by placing them adjacent the middle of these plates, the diaphragm is virtually subdivided into a number 20 of smaller diaphragms, and its freedom to respond to the more delicate impulses brought to bear upon it by the condenser plates is greatly improved.

I point out, in addition, that in my device 25 the diaphragm, though made of considerable area, is easily actuated throughout practically its entire area, and that this fact makes for greatly improved efficiency.

While I show my invention as adapted for 30 use in connection with an aerial and thus as under control of electromagnetic waves, it will be understood that I may substitute any known equivalent for the aerial, and thus may control my device by means of a telephone line or by any other agency capable of 35 energizing an audion or equivalent instrument in the conventional manner. Thus the particular circuit shown and described is not essential.

40 The principal characteristic of this invention is the use, in connection with one or more condenser plates adapted to be charged to varying degrees of potential, of a diaphragm made of insulating material and 45 adapted to be attracted and repelled electrostatically thereby, so as to produce acoustical vibrations.

While I have shown and described a particular means for holding the plates and the 50 diaphragm in their respective operative positions nevertheless any other appropriate means may obviously be employed to this end.

It will also be understood that I claim for 55 my loud speaker all of the uses to which a loud speaker can be applied, and in addition, it should be noted that while for the sake of simplicity I show in each form of my invention only a single pair of condenser plates, any number of these plates, arranged in pairs, may be grouped together for the purpose of increasing the size, strength, or capacity of the device as a whole.

65 As many changes could be made in this 130 ing two plates of conducting material spaced

construction without departing from the scope of the invention as defined in the following claims, it is intended that all matter contained in the above description or shown in the accompanying drawings shall be interpreted as illustrative only and not in a limiting sense.

Having thus described my invention, what I claim as new and desire to secure by Letters Patent is:—

1. A device of the class described comprising two plates of conducting material spaced apart and insulated from each other, an acoustical diaphragm made of insulating material and located between said plates of 80 conducting material, and means for subjecting said plates of conducting material to varying potentials in order to cause said plates to attract and repel said diaphragm and thus to actuate said diaphragm.

2. A device of the class described comprising two plates of conducting material spaced apart and insulated from each other so as to serve as condenser plates, a diaphragm 90 of insulating material disposed between said plates, and electric means connected with said plates and controllable by electric variations for the purpose of causing one of said plates to attract, and the other of said plates to repel, said diaphragm.

3. A device of the class described comprising two plates of conducting material spaced a slight distance apart in substantially parallel relation to each other and insulated from each other, means to variably electrically excite said plates, and a diaphragm 100 of insulating material disposed between said plates to be actuated by the electrical variations thereof.

4. A device of the class described comprising two plates of conducting material spaced a slight distance apart in substantially parallel relation to each other and insulated from each other, holding means for said plates, means to variably electrically excite 105 said plates, and a diaphragm of insulating material disposed between said plates held by said holding means and adapted to be actuated by the electrical variations of said plates.

5. A device of the class described, comprising a pair of plates of conducting material insulated from each other and serving as condenser plates, a diaphragm of insulating material disposed between said plates and free to vibrate in response to attractions and repulsions thereof, a source of electricity for charging said plates to varying potentials and a circuit bridged across said plates and connected with said source of 120 electricity, said circuit including an impedance for retarding the action of one of said plates relatively to the other.

6. A device of the class described comprising 125 two plates of conducting material spaced

1
a slight distance apart in substantially parallel relation to each other and insulated from each other, means to variably electrically excite said plates, a diaphragm of insulating material disposed between said plates to be actuated by the electrical variations thereof, and means carried by said plates projecting therefrom to press against

the diaphragm at various spaced points throughout the extent of the diaphragm to 10 thereby hold said spaced points firmly between the two plates for the purpose described.

In testimony whereof I affix my signature.

JOHN DEPEW.
